THERMOSTATIC DEVICE

Benson F. Waddell, Jackson Heights, N. Y., assignor to The Wilcolator Company, Newark, N. J., a corporation of Delaware

Application March 25, 1936, Serial No. 70,762

14 Claims. (CL 236—15)

This invention relates to thermostatic regulators for gas ranges, and particularly to a regulator for that use which includes both a thermostatically actuated valve, controlling the rate of flow of gas, and a manually actuated valve by which the flow of gas may be turned on or cut off at will.

One of the features of the invention involves the provision of a novel construction of the cut-off valve and the parts associated therewith. This includes a rotatable valve-member having a longitudinal passage therethrough and an adjustment means extending through this longitudinal passage and employed for adjusting the connection between the thermostatic element of the regulator and the valve by which the rate of flow of gas is regulated. The cut-off valve and the regulating valve are mounted in a casing having a seat for the cut-off valve and a gas port opening into the seat, and the cut-off valve and adjustment means together define a gas way extending along the adjustment means to the interior of the casing and adapted to connect the regulating valve and the gas port when the cut-off valve is in its "on" position. The gas way may be conveniently provided by forming the cut-off valve with a lateral opening which is movable into and out of alignment with the port by rotation of the valve, and mounting the adjustment means in the cut-off valve with a clearance between the adjustment means and the wall of the longitudinal passage, the clearance forming a gas way in the cut-off valve extending inwardly along the adjustment means from the lateral opening and communicating at its inner end with the regulating valve. Preferably, the cut-off valve and the thermo-responsive element for the regulating valve are mounted at opposite ends of the casing, and the adjustment means includes an actuator connected to the regulating valve and disposed between the cut-off valve and the thermo-responsive element, the actuator being operable by the element through a connection which is adjustable by rotation of the adjustment means.

This assemblage of the cut-off valve and the adjustment means extending therethrough may be so formed as to provide a gas-tight seal between the adjustment means and the outer end of the gas way. A portion of the adjustment means or of an enlargement thereon may have a frusto-conical surface cooperating with a similar surface on the interior of the cut-off valve, these surfaces fitting together so tightly as to make an effective gas-tight seal.

Another feature of the invention resides in the provision of means for effecting the connection of the regulator to the manifold pipe of the range. For this purpose, a nipple is employed which is adapted to be secured to the manifold pipe, preferably by screwing it into an opening provided in the pipe. This nipple is arranged to facilitate connecting the regulator to it with a gas-tight joint by a simple mechanical operation, as the tightening of a pair of screw-bolts. Such a construction has many advantages. The nipple may be very short and therefore the handle of the regulator may be in line with the gas-cocks of the range, as is desirable from the standpoint of appearance. Also, the nipple may be assembled on the manifold before the latter is mounted on the range. With that done, the mounting of the regulator involves only inserting it through an opening in the front plate of the range and attaching its casing to the nipple with the bolts provided for the purpose, and the joint so made possesses all of the requisite strength. Furthermore, by this construction the regulator may be detached at any time for inspection or repair and a different regulator may be substituted without requiring detachment of the nipple.

Another feature of the improved regulator involves the construction and arrangement of the two handles, one for effecting regulation of the valve for temperature adjustment, and the other for turning the shut-off valve to open and closed positions. These two handles are in axial alignment, and the handle for the shut-off valve is at the front; the connections from this handle to the shut-off valve extend over the other handle for effecting the regulation. Such a construction is convenient and compact and may be of attractive appearance and permits of making the regulator in such form that it may be mounted in position by inserting it through an opening of corresponding size provided for its reception in the front plate of the range.

These and other features of the improved regulator will be better understood by reference to the following description taken in connection with the accompanying drawings which show the preferred embodiment of the invention.

In these drawings:

Fig. 1 is a vertical, longitudinal, sectional view; 50

Fig. 2 is a top plan view;

Fig. 3 is a detailed, sectional view on line 3—3 of Fig. 1;

Fig. 4 is a similar view on line 4—4 of Fig. 1;

Fig. 5 is a similar view on line 5—5 of Fig. 1; 55

- Fig. 6 is a vertical, longitudinal, sectional view of another form of the invention;
- Fig. 7 is a plan view of the valve operating mechanism and adjusting means of the form shown in Fig. 6;
- Fig. 8 is a horizontal, sectional view on the line 8—8 of Fig. 6;
- Fig. 9 is a transverse, vertical, sectional view on line 9—9 of Fig. 6;
- Fig. 10 is a similar view on line 10—10 of Fig. 6;
- Fig. 11 is a similar view on line 11—11 of Fig. 6;
- Fig. 12 is a front elevation of a blank used in forming a portion of the manually operated valve mechanism; and,
- Fig. 13 is a front elevation of the latch plate in the form shown in Figs. 6 to 8.
- The regulator is preferably of the type employing a thermo-responsive liquid contained in a closed system including a bulb located within the oven, a flexible metal tube extending from the bulb to the exterior of the oven, and an expandable and contractable chamber connected to the outer end of the tube. A regulator of this type is described in Patent No. 1,978,362 granted October 23, 1934. It will be apparent, however, that the features of the invention may be employed in thermostatic regulators of other types.
- Referring to the drawings, the bulb adapted to be mounted within the oven is shown at 1, and the tube leading therefrom at 2. At its outer end this tube is connected to the regulator casing or a part mounted thereon. This casing is shown at 3 and it is adapted to be secured as hereinafter described to the manifold 4 of the range. At its rear end the casing 3 is provided with an opening over which is secured a cup 5, and a flexible metal bellows 6 is sealed within this cup to form an annular space 7 between the cup and bellows constituting an expandable and contractable chamber. The end of the cup 5 is sealed by a gasket 8 located between a flange 9 on the cup and an annulus 10. A disc 11 lies against the closed end of the bellows and a rod 12 secured at its end to this disc extends through the central opening in the annulus 10. A spring 13 is arranged between the disc 11 and annulus 10 and tends to keep the bellows expanded by urging the rod 12 toward the right as shown in Fig. 1.
- Beyond the annulus 10, the rod 12 is provided with a threaded portion 14. A square nut or actuator 15 is arranged on the threaded end of the rod and the flat sides 16 of the nut lie adjacent the inner sides of a square sleeve 17. The nut is provided with a reduced end forming a shoulder 18 and a bimetallic compensating thermostatic lever 19 is adapted to engage the shoulder. The end of the thermostatic lever is pierced to fit over the reduced portion of the nut 15 and to have contact with the shoulder 18. The thermostatic lever is pivotally supported on a pin 20 and beyond the pivot it is connected to the stem 21 of the valve-member 22. This valve-member 22 cooperates with a valve-seat 23 formed in the casing to form a regulating valve. The valve-member is urged toward its seat by a coil spring 24 engaging the valve-member and a valve-cap 25 which closes an opening in the casing through which access may be had to the valve. The chamber 26 formed on the outlet side of the valve is provided with outlet openings 27 on opposite sides as shown in Fig. 2 of the drawings. Either of these openings may be connected to a pipe 28 leading to the oven burners (not shown) and the other closed by a plug. The provision of the two openings allows greater flexibility in

installing the device on various types of stoves in which the position of the oven with respect to the stove top may be reversed in some instances.

The square sleeve 17 is connected to an adjusting device which may take various forms but which in the form illustrated comprises a rod or shaft 29 which projects through the front of the valve casing and receives a handle 30 to permit adjustment of the regulator. In the forward portion of the valve casing is a conical section forming a seat for the rotatable valve-member 31 of a cut-off valve. This valve is provided with an inlet opening 32 adapted to be aligned with the inlet pipe when the valve is in open position. This cone-shaped valve-member 31 and the correspondingly shaped portion of the casing forming its seat have their larger ends toward the rear of the device or away from the handle.

The gas inlet of the regulator is through a nipple 33 connected with the manifold 4 by threads as shown and having the casing of the regulator secured to it by bolts 36 as such a construction presents the advantages referred to above. This nipple 33 is externally threaded and is screwed into the manifold pipe 4 before the latter is mounted on the range and at the time when the gas cocks of the top burners are connected to the manifold. Also the nipple may be quite short with the result that the regulator may be so close to the manifold as to have its handle in line with the burner handles across the front of the range. The nipple 33 has an enlarged and flanged lower end 34 recessed to receive a gasket 35 which aids in forming a gas-tight union between the bottom face of the nipple 33 and a coacting machined face on the casing. The casing and the flange 34 are provided with aligned openings adapted to receive screws 36 to secure the valve casing to the fitting.

The valve-member 31 is operated by a handle 37 which is arranged on a reduced extension of the regulator handle 30. As shown, the valve-member 31 extends beyond the end of the casing 3, and is provided with a threaded portion 38. A disc 39 is secured to this threaded extension by jam nuts 40. The disc 39 is provided with a pair of diametrically spaced notches 41 adapted to receive the ends of arms 42 secured to and extending rearwardly from the handle 37. When the handle 37 is turned, turning the disc 39, the plug valve 31 will also be turned. Locking means are provided for maintaining the valve in the off position and preventing accidental operation thereof. As shown, the arms 42 extend in the rear of the disc 39 and are provided with forked ends to receive a spring member 43 which is mounted on the valve-member 31 back of the disc 39 to rotate therewith. One end of this spring member is adapted to engage latch 44 when the valve is in the off position. This latch 44 is carried by a plate 45 mounted on the bottom of the valve casing. To release the valve operating means, slight pressure is applied axially of the valve casing moving the end of the spring member 43 out of the latch and permitting rotation of the valve-member. The control means of valve-member 31 is also provided with a stop to prevent movement beyond its fully opened position. As shown, the valve casing is provided with a shoulder 46 adapted to engage a corresponding shoulder 47 formed on a cup-shaped member 48 which is retained in position on the valve-member 31 to rotate therewith by the jam nuts 40. The cup-shaped member 48 abuts a

shoulder 49 formed at the inner end of the threaded portion 38 of the valve-member 31. A spring 50 is mounted in the cup-shaped member between it and the valve casing and normally urges the valve assembly and operating mechanism toward the front of the valve casing.

The arms 42 may be connected to the handle 37 in either of two positions to permit the gas cock handle of the present device to be arranged in the same way as the gas cock handles of the top burners of the range. In some instances the gas cock handles are so placed that the off position is horizontal while in others it is vertical. In the drawings the gas cock handle of the present apparatus is shown in a vertical position when the valve is open but it may also be arranged in a horizontal position. As shown in Fig. 1 the handle 37 is recessed to receive a ring 51 carried by arms 42. This ring is provided with radially extending projections 52 adapted to be received in similar recesses in the body portion of the handle. The handle is provided with four of such recesses 53 (see Fig. 5) arranged at 90° from each other. By placing the projections 52 in one set of recesses 180° apart, the handle may be so positioned that it will be horizontal when the valve is closed and by placing it in the other two recesses at 90° from each of the first two recesses, the handle may be arranged so that it will be vertical when in the off position.

The handle 30 is connected to the rod or shaft 29 to provide adjustment of the position of the manually operated parts with respect to the valve casing. There is considerable variation in the distance between the manifold and the front panel of different types of ranges and it is even true that this distance will vary in individual ranges of the same model. This means that the position of the operating handles must be changed with respect to the valve in order to produce an assembly that is pleasing. Heretofore such variations have necessitated different lengths of stems and valve extensions. In the present invention I provide an adjusting means which permits the use of a rod 29 of uniform length. As shown, the disc 39 is adapted to be aligned with the front panel 54 of the range. A dial 55 is arranged on the rod 29 immediately forward of this disc. This dial is provided with the usual 50 graduations to indicate temperatures that will be attained in the oven for various settings of the thermostatic regulator. The graduations of the dial may cooperate with a suitable stationary marker (not shown) on the front panel. The handle 30 is provided with a metallic central threaded insert 56 which engages threads on the end of rod 29. Dial 55 is clamped between two washers 58 and 59. The forward washer 58 is provided with a square central opening adapted to receive a squared end 60 of the insert 56. The washer 59 is provided with keys 61 engaging key ways 62 in the rod 29. The dial is held between the washers by screws 63 which secure the washers to each other. It is urged outwardly on the rod 29 by a spring 64.

I provide means for lubricating the valve-member 31 to prevent it from sticking. As shown, the latch plate 45 is carried by a boss 65 on the bottom of the valve casing. This boss is provided with an inclined bore 66 threaded at its outer end to receive a screw 67. The inner end of the bore communicates with the valve casing adjacent the plug valve. It will be apparent that this bore may be filled with grease or other lubricant and the lubricant may be forced into the

valve casing by moving the screw 67 inwardly. The grease thus placed in the valve casing can be distributed along the valve-member 31, by moving the valve assembly back and forth. Pressing inwardly on the handle 37 causes the valve assembly to move and springs 50 and 64 return the parts to their original position.

In operation, the valve-member 22 is pressed toward the closed position by spring 24. When the oven is to be set for a desired temperature, rotation of handle 30 moves the nut 15 along the threaded portion 14 of rod 12 and the shoulder 18 bears against the thermostatic lever 19 causing it to open the valve-member against the tension of the spring. If the gas cock is opened by rotating the valve-member 31 and the oven lighted, as the temperature of the oven rises, the thermo-responsive liquid in bulb 1 expands, thus compressing the bellows 6 against the tension of spring 13, moving the shoulder 18 of nut 15 and permitting the thermostatic lever 19 to move under the pressure of spring 24. This causes the other end of the lever to move toward the right, permitting the valve-member 22 to adjust itself to cut down the supply of gas. Upon a drop in temperature in the oven the bellows expands and causes the valve-member to increase the supply of gas. The lever 19 connecting the valve-member to the rod 12 is a bimetallic thermostat and serves as a compensating thermostat to offset the effect of temperatures outside the oven on the device. It will be apparent that a portion of tube 2 and annular space 7 containing the thermo-responsive liquid are outside the oven and are subject to changes of temperature caused, for instance, by lighting the top burners of the range. In the absence of a compensating thermostat these extraneous temperatures would cause false operation of the valve-member 22. The bimetallic lever 19, however, is set to operate against the main thermostatic element and inasmuch as it is also exposed to the same external temperatures it will offset or compensate for any false movement that would otherwise be imparted to the valve-member 22 by the effect of extraneous temperatures upon the portions of the main thermostatic element outside the oven.

The adjustment of the thermostatic element is made through the handle 30 in the manner heretofore described and the main gas cock is opened and closed by manipulation of the handle 37 in the manner heretofore described. The construction and arrangement of parts facilitates the connection of the valve assembly to the manifold and permits the fitting 33 to be attached to the manifold at the same time as the fittings used for the gas cocks of the main top burners. As stated, this can be done before the manifold is assembled on the range and the valve casing may then be readily connected to the fitting by the screws 36. The adjustability of the dial and handle assembly on the end of the rod 29 permits the parts to be adjusted with respect to the front panel 54. The parts are so arranged that the handle 30 and the handle 37 may be aligned with the handles of the gas cocks of the main top burners producing a pleasing assembly. The greasing device is of advantage in that it permits lubrication of the valve-member 31 without disassembling the parts if the valve should stick.

In the form of the invention shown in Figs. 6 to 13 of the drawings, the construction of the main thermostatic element, the valve casing, the regulating valve and associated parts is substan-

tially the same as that heretofore described and similar reference numerals are applied to like parts. In Fig. 6 I have shown the casing provided with a small opening 25 to which a suitable connection may be made (not shown) to deliver sufficient fuel to operate a pilot burner. This is a feature of usual construction in devices of this character and the form of the invention illustrated in Figs. 1 to 5 may also be provided with a pilot opening of this type.

10 The rod or shaft 29 is constructed substantially as heretofore described in connection with Figs. 1 to 5 but the valve arrangement is of a different form and the means for controlling the valve 15 and the means for adjusting the connections between the main thermostatic element and the regulating valve are modified. As shown a valve-member 70 surrounds the rod 29 and this valve is of the cone type, with its larger end toward 20 the front. It is provided with an opening 71 communicating with an inlet port 72 in the casing. As shown, the inlet port is adapted to be connected to the manifold 4 by a fitting 73 generally similar to that shown in Fig. 1. In the fitting 25 shown in Fig. 6, however, the recessed gasket seat is omitted and a gasket 74 is arranged between the adjacent surfaces of the valve casing and the fitting. The fitting is threaded into an opening in the manifold as shown and is secured to the 30 valve casing by screws.

The rod 29 is provided with an enlargement 75 which fits within the bore of the valve-member 70. The valve-member 70 is retained against the bore of the casing by a coil spring 76 which 35 abuts against a shoulder 77 formed on the exterior of the valve-member and against a latch plate 78 which is secured to the valve casing by screws and is stationary. The construction of this latch plate is shown in Fig. 13 of the drawings. As shown, it is provided with openings 79 for the fastening elements and is further provided with diametrically opposed notches 80 which cooperate with a yoke to lock the valve 40 in the off position. The latch plate is also provided with a pair of lugs or ears 81 that stick up from the surface of the latch plate and are adapted to secure a key plate 82 (see Fig. 12) in 45 position. The key plate is in the form of a disc provided with diametrically opposite flattened portions 83 and with a pair of diametrically opposite ears 84 arranged between the flattened portions. It is also provided with a central opening 85 having enlargements 86. When these two plates are assembled the plate 82 is first turned 50 45° in a clockwise direction from the position shown in Fig. 12 to bring the enlargements 86 in alignment with the ears 81 and is then turned counter-clockwise 45° to the position shown in Fig. 12 to bring the outer edge over the notches 80 of the latch plate 78 as shown in Fig. 6. The flattened portions 83 may be turned to be in 55 alignment with notches 80 for the removal of the arms 87.

The latch plate 78 and the key plate 82 cooperate with arms 87 by means of which the valve-member 70 is actuated. As shown, these arms pass through notches 88 in a disc 89 which is mounted on the extended portion of the valve-member whereby rotation of the arms causes the disc and valve-member to rotate therewith. The extended portion of the valve-member is flattened on opposite sides at 90 as shown in Fig. 11 and the disc 89 is provided with a central opening surrounded by a flange 91, the opening and flange having flattened portions corresponding to

the flattened portions 88 of the valve member. The arms 87 are connected to a handle 92 having a central bore which receives the end of the rod 29. A spring 93 is arranged in the bore of the handle and normally forces it outwardly. 5 The spring abuts against a washer 94 surrounding the rod 29 to normally retain the arms 87 and their associated parts in a forward position. The ends of the arms 87 are offset inwardly as indicated at 95 (see Fig. 9) and are adapted to 10 be received in the notches 80 of the latch plate against the key-plate 82 when the valve-member is in an off position to prevent accidental opening of the valve-member. To open the valve-member the handle is pushed inwardly against 15 the tension of spring 93 to remove the ends 95 of the arms from the notches 80. The valve-member may be then turned toward the open position. The disc 89 may be provided with an extension 96 containing suitable indicia to indicate 20 that the valve is open and the arm 87 which is in the upper position when the valve is closed may be provided with suitable indicia as indicated at 97 to show that the valve is in the off position.

25 The thermostatic regulating means consists of a suitable calibrated drum 98 mounted between the plug disc 89 and the base of the arms 87. As shown the drum is mounted on a hollow sleeve 99, the rear portion of which is of suitable diameter to receive the drum and said rear portion is provided with a flange 100 against which the drum abuts. The forward portion 101 of the sleeve is substantially of the diameter of the rod 29 and is keyed to the rod as indicated at 102. 30 The drum is provided with a recess at its forward end adapted to receive a collar 103 which is mounted on an intermediate portion 104 of the sleeve 99. This collar is provided with a threaded opening to receive an adjusting screw 105 which 35 engages the sleeve 99. By loosening the screw 40 the drum may be adjusted on the sleeve for calibrating the instrument.

The outer end of the rod 29 is threaded and as 45 shown in Fig. 8 a nut 106 is arranged on the threaded portion of the rod. A spring 107 surrounds the rod between this nut and the adjacent end of the valve member. This exerts an outward pressure on the rod to retain the enlargement 75 in snug engagement with the bore of the valve-member.

The operation of this form of the invention will be apparent from the foregoing description. Actuation of the arms 87 through the handle 92 permits opening and closing of the manually operated valve-member 70 and the connection between the main thermostatic element and the regulating valve-member 22 is adjusted for any desired temperature by turning the drum 98 to rotate the rod 29 and thus adjust the nut 15 on 55 the threaded end of the rod 12.

60 It will be apparent that in the two illustrated forms of the invention, the adjustment means including the elongated device 28 and the actuator 15 serves the dual function of adjusting the temperature setting of the regulating valve and partly defining a sealed gas way in the cut-off valve extending inwardly along the adjustment means from the lateral opening in the cut-off valve and communicating at its inner end with the regulating valve. By arranging the cut-off valve and the thermo-responsive element 12 at 65 opposite ends of the casing and locating the actuator 15 for the regulating valve between them, I provide a compact construction in which 70 75

the actuator may be operatively connected to both the thermo-responsive element and the adjustment device 29 through simple and direct connections.

5 In each of the illustrated forms of the invention, the part 29 of the adjustment means is fitted closely in the front part of the cut-off valve so that there is considerable friction between these two parts, and since the actuating nut 15 offers but slight resistance to turning of the adjustment means, the friction causes the adjustment means to turn with the cut-off valve. Accordingly, the adjustment dial may be set to a desired temperature when the cut-off valve is in 10 its "off" position, and, when the handle for the cut-off valve is rotated to turn on the latter valve, the dial and other parts of the adjustment means will move with the handle and remain at the desired setting. However, when the adjustment 15 dial is turned, the adjustment means moves independently of the cut-off valve, because the latter is held against movement by its tight fit in the casing. It will be understood that the separate handle for the adjustment means may be 20 omitted, if desired, and the temperature adjustment effected by the movement of the part 29 with the cut-off valve, in which case the lateral opening in the side wall of the cut-off valve is elongated circumferentially so that the handle 25 for the cut-off valve may be turned through a considerable angle to move the adjustment means to the desired temperature setting without closing the cut-off valve. When this construction is employed, the adjustment means is rotated 30 relative to the cut-off valve to calibrate the instrument, and to this end the rod 29 may project through the handle and be provided with a set screw which may be easily manipulated to effect 35 the calibration.

40 I claim:

1. A thermostatic controller comprising the combination of a valve member having an opening through its side wall, a control means passing through the valve member and rotatable relative thereto, the member and rod being formed to provide a gas passage between them from said opening through the inner end of the valve member, a casing provided with a seat for the valve member and an opening through the seat adapted to cooperate with the opening in the valve member, an operating device for moving said openings into and out of alignment, a gas regulating valve for controlling flow through said valve member and comprising a seat and a valve member movable relatively to the seat, the casing having a gas passage therein leading from said last valve member to said end of the first valve member, a thermo-responsive means connected to the regulating valve for regulating the relative positions of its valve member and seat, and means whereby the turning of the control means effects an adjustment of the relation between said thermo-static element and the gas regulating valve.

2. A thermostatic controller comprising the combination of a tubular valve member having an opening through its side wall intermediate its ends, a rod passing through the tubular member and rotatable relative thereto, the rod and member being formed to provide a space between them leading from said opening out through the inner end of the valve member and surfaces on the member and rod on the opposite end of said valve member coacting to form a gas-tight seal, a casing provided with a seat for the valve member, and an opening through the seat adapted to

cooperate with the opening in the valve member, an operating device for moving said openings into and out of alignment, a gas regulating valve for controlling flow through said valve member and comprising a seat on the casing and a valve member movable relatively to the seat, the casing having a gas passage therein leading from said last valve member to said first end of the tubular valve member, a thermo-responsive means connected to the valve for regulating the relative positions of its valve member and seat, a handle independent of said operating device for turning said rod, and means whereby the turning of the rod effects an adjustment of the relation between said thermostatic element and the gas regulating valve.

3. In a gas control valve, a casing having a valve seat formed thereon and provided with a port for the admission of gas, a hollow cut-off valve in the casing coacting with said seat and having a central opening through one end thereof and an opening through its side wall adapted to cooperate with said port, a handle for turning the valve to control the flow of gas into and through the valve, a regulating valve in the casing controlling the flow of gas passing through the hollow cut-off valve, the casing having a gas passage leading from the regulating valve to said central opening in the cut-off valve, a thermostatic element controlling the operation of the regulating valve, and an operating device passing through the hollow cut-off valve into said passage for adjusting the relation between the thermostatic element and the regulating valve independently of the cut-off valve and fitted in said central opening with a clearance between said device and the edge of said central opening.

4. In a gas oven control, a casing having a cone-shaped valve seat therein and having a port for the admission of gas, a hollow cone-shaped cut-off valve therein having a central opening through one end thereof and an opening in its side wall cooperating with said port, a handle concentric with the valve and connected to it for turning it relatively to its seat, a regulating valve in the casing controlling the flow of gas passing through the hollow cut-off valve, the casing having a gas passage leading from the regulating valve to said central opening in the cut-off valve, a thermostatic element controlling the operation of said regulating valve, a regulating means for adjusting the relation between the thermostatic element and the regulating valve independently of said cut-off valve, said means passing through the cut-off valve into said passage and being fitted in said central opening with a clearance between said means and the edge of the opening to permit flow of gas through said end of the cut-off valve and along said means, said means closing the opposite end of the cut-off valve, and a handle for operating said regulating means mounted concentric with the handle of the cut-off valve.

5. In a thermostatic fuel control, a casing, a thermostat at the rear end of the casing, a valve actuator in the casing, an adjustable connection between the actuator and thermostat, a hollow cut-off valve arranged in the front end of the casing and having an opening through its side wall and a central opening through its rear end, a port in the side wall of the casing cooperating with said side opening in the cut-off valve, rotatable adjustment means extending through the cut-off valve for adjusting said connection, said means being fitted in the central opening in the cut-off valve with a clearance between said means

and the edge of the central opening, a regulating valve in the casing offset laterally from the axis of said adjustment means and connected to the actuator, the casing having a gas passage leading 5 from the central opening in the cut-off valve to the regulating valve, means at the front end of the casing for operating said adjustment means, and means for actuating the cut-off valve arranged concentrically with said adjustment 10 means and operable independently thereof.

6. In a thermostatic controller comprising a casing, a thermo-responsive valve in the casing, a rod projecting from the casing and rotatable to adjust the valve, and a shut-off valve concentric with the rod and operable to control the passage of gas through the first valve, the combination of a collar keyed to the projecting part of the rod and removable off the end thereof, manual operating means for the shut-off valve located 15 near the end of the rod and operable to secure the collar against removal therefrom, said last means being removable from the casing, releasable locking means for securing the manual means against removal from the casing, and a dial secured to the collar and adjustable thereon to calibrate the controller, said collar, dial and manual means being removable from the casing upon release of said locking means.

7. In a thermostatic controller comprising a casing, a thermo-responsive valve in the casing, a rod projecting from the casing and rotatable to adjust the valve, and a cut-off valve concentric with the rod and operable to control the passage of gas through the thermo-responsive valve, the 30 combination of a handle for the rod, said handle being mounted on the rod and movable off one end thereof, a plate disposed on one side of the handle between the handle and casing and operatively connected to the cut-off valve, a handle 35 for the cut-off valve on the opposite side of the first handle and concentric therewith and rotatable independently thereof, said second handle being removable from the casing and securing the first handle against removal from the rod, connecting means between the second handle and the plate extending over the first handle and projecting beyond the plate toward the casing, said projecting portion of the connecting means having a part extending at substantially right 40 angles to the body of the connecting means, and a locking plate supported by the casing and rotatable relative thereto and having a part of its periphery located in front of and in alignment with said part of the connecting means to secure 45 the second handle against removal, the locking plate being rotatable to move said parts out of alignment and thereby permit removal of said handles.

8. In a device of the character described comprising a cut-off valve, a thermo-responsive regulating valve controlling flow through the cut-off valve, a casing for said valve, and an operating device for adjusting the thermo-responsive valve and removable from the casing, the combination 60 of a handle operatively connected to the cut-off valve and securing the operating device against removal from the casing, said handle being displaceable axially and removable from the casing, a latch plate secured to the casing in back of the 65 handle and provided with a peripheral slot, a key plate rotatably mounted in front of the latch plate and having a part adapted to cover said slot, and a member on the handle having a part engaging the back of the key plate to secure the 70 handle against removal and disposed in said 75

slot to secure the handle against rotation, the handle being movable axially to remove said part from the slot and permit rotation of the handle, and the key plate being rotatable to uncover the slot and permit removal of the handle and operating device. 5

9. A thermostatic controller comprising the combination of a valve member having an opening through its side wall, a rod passing through the valve member and rotatable relative thereto, 10 the member and rod being formed to provide a gas passage between them from said opening to the inner end of the valve member, a casing provided with a seat for the valve member and an opening through the seat adapted to cooperate 15 with the opening in the valve member, the rod being fitted in said inner end of the valve member with a clearance between the rod and valve member and having a part projecting inwardly beyond said end into the casing, the casing being 20 provided with a chamber surrounding said projecting part of the rod and forming a continuation of said gas passage, a gas regulating valve in the casing for controlling flow through said valve member and communicating with the inner 25 end of said chamber, adjustable thermo-responsive means for actuating the regulating valve and located in said chamber between the inner end of the cut-off valve and the rear end of the casing, means connected to said projecting part 30 of the rod in the chamber whereby turning of the rod effects an adjustment of the regulating valve, and operating devices outside the casing for independently actuating said rod and valve member. 35

10. A thermostatic controller comprising a casing having an elongated passage extending through the front end thereof, a hollow cut-off valve fitted tightly in the front part of the passage and rotatable therein and having an opening in its side wall, the casing having a port leading into said passage and cooperating with said opening, an operating device in front of the casing for rotating the cut-off valve to move said opening and port into and out of alignment, 40 the cut-off valve having an axial bore therethrough leading into said passage, a thermo-responsive element in the casing located in said passage in back of the rear end of the cut-off valve, a regulating valve in the casing for controlling flow through the cut-off valve, a connection between the thermo-responsive element and regulating valve, a rod extending through said bore into the passage and sealing the front end 45 of the bore and rotatable therein, the rod having a clearance with the wall of the rear part of the bore to permit the flow of gas along the rod between said opening and the rear part of the passage, and means in the rear part of the passage operatively connecting the inner end of the 50 rod to said first connection, whereby rotation of the rod adjusts the regulating valve. 55

11. In a gas regulator, a casing having a valve seat in the front end and a gas port opening into the seat, a hollow cut-off valve coacting with 60 the seat and rotatable in the casing, the valve having a lateral opening and a longitudinal passage leading inwardly from the opening into the casing, means for rotating the cut-off valve to move said port and opening into and out of alignment, a thermo-responsive element in the 65 casing at the opposite end, a temperature regulating valve operable by the thermo-responsive element to control the rate of flow through the cut-off valve and including a valve member and 70 75

5 a seat, and adjustment means for the regulating valve passing through the passage in the cut-off valve and mounted for rotation therein independently of the cut-off valve with a clearance between the adjustment means and the wall of the passage, the clearance forming a gas way along the adjustment means between the regulating valve and said lateral opening; the adjustment means including an actuator connected to the 10 regulating valve and located between the cut-off valve and the thermo-responsive element and having a threaded connection with said element, whereby rotation of said means adjusts the threaded connection and varies the relation between the thermo-responsive element and the actuator.

12. In a gas regulator, a casing having a valve seat and a gas port opening into the seat, a hollow cut-off valve in the casing coacting with the 15 seat and rotatable in the casing, the valve having a lateral opening through its side wall intermediate its ends and adapted to align with said port, the valve also having a longitudinal passage therein extending from said lateral opening toward the inner end of the valve, a handle for turning the valve to move said lateral opening into and out of alignment with the port, a manually adjustable temperature regulating valve in the casing controlling the flow of gas 20 passing through the cut-off valve and including a valve member and a seat, a thermo-responsive element controlling the operation of the regulating valve and located in the casing beyond the inner end of the cut-off valve, adjusting means 25 extending through said passage in the cut-off valve, said adjusting means being mounted for rotation in the cut-off valve independently thereof and with a clearance between the adjusting means and the wall of said passage in the cut-off valve, the space provided by said clearance forming a gas way along the adjusting means 30 between the regulating valve and the lateral opening in the cut-off valve, and an operative connection between the inner part of said adjusting means and the regulating valve for adjusting the regulating valve when said adjusting means is rotated.

40 13. In a gas regulator, a casing having a valve

5 seat and a gas port opening into the seat, a hollow cut-off valve in the casing coacting with the seat and rotatable in the casing, a manually adjustable temperature regulating valve in the casing for controlling flow through the cut-off valve and including a valve member and a seat, a thermo-responsive element controlling the regulating valve and located in the casing beyond the inner end of the cut-off valve, adjusting means 10 extending through the cut-off valve generally parallel to the axis thereof, the adjusting means being mounted for rotation independently of the cut-off valve and defining with the cut-off valve a gas way extending partly along the adjusting means, the gas way being adapted to connect said port with the regulating valve, a handle for turning the cut-off valve to move a part of said gas way into and out of alignment with the port, and an operative connection between the inner part of said adjusting means and the regulating 15 valve to adjust the regulating valve when the adjusting means is rotated.

14. In a gas regulator, a casing having a valve seat and a gas port opening into the seat, a hollow cut-off valve in the casing coacting with the seat and rotatable in the casing, a manually adjustable temperature regulating valve in the casing for controlling flow through the cut-off valve and including a valve member and a seat, a thermo-responsive element controlling the regulating valve and located in the casing beyond the inner end of the cut-off valve, adjusting means 20 extending through the cut-off valve generally parallel to the axis thereof, the adjusting means being mounted in the cut-off valve for rotation therewith but also being rotatable relative to the cut-off valve, the cut-off valve and the adjusting means together defining a gas way in the cut-off valve extending partly along the adjusting means and adapted to connect said port with the regulating valve, a handle for turning the cut-off valve to move a part of said gas way into and out of alignment with the port, and an operative connection between the inner part of said adjusting means and the regulating 25 valve to adjust the regulating valve when the adjusting means is rotated.

30 15. In a gas regulator, a casing having a valve seat and a gas port opening into the seat, a hollow cut-off valve in the casing coacting with the seat and rotatable in the casing, a manually adjustable temperature regulating valve in the casing for controlling flow through the cut-off valve and including a valve member and a seat, a thermo-responsive element controlling the regulating valve and located in the casing beyond the inner end of the cut-off valve, adjusting means 35 extending through the cut-off valve generally parallel to the axis thereof, the adjusting means being mounted in the cut-off valve for rotation therewith but also being rotatable relative to the cut-off valve, the cut-off valve and the adjusting means together defining a gas way in the cut-off valve extending partly along the adjusting means and adapted to connect said port with the regulating valve, a handle for turning the cut-off valve to move a part of said gas way into and out of alignment with the port, and an operative connection between the inner part of said adjusting means and the regulating 40 valve to adjust the regulating valve when the adjusting means is rotated.
